US0D1066117S

(12) **United States Design Patent** (10) Patent No.: **US D1,066,117 S**
(45) Date of Patent: ** Mar. 11, 2025

(54) **BUCKLE**

(71) Applicant: **CARTIER INTERNATIONAL AG**,
Steinhausen (CH)

(72) Inventor: **Fabrice Colin**, Paris (FR)

(**) Term: **15 Years**

(21) Appl. No.: **35/519,192**

(22) Filed: **Sep. 1, 2023**

(80) **Hague Agreement Data**

Int. Filing Date: **Sep. 1, 2023**

Int. Reg. No.: **DM/232136**

Int. Reg. Date: **Sep. 1, 2023**

Int. Reg. Pub. Date: **Dec. 1, 2023**

(30) **Foreign Application Priority Data**

Mar. 2, 2023 (WO) WIPO129490
